Primary Examiner — Sandra Snapp*Assistant Examiner* — Bryan N. Melvin**CLAIM**

The ornamental design for a wireless charger as shown and described.

DESCRIPTION

FIG. 1 is a front, right, and top perspective view of a wireless charger, showing my new design;

FIG. 2 is a rear, left, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is a cross-sectional view thereof, taken along the section line 9-9 as depicted in FIG. 3.

The broken lines in the drawings depict portions of the wireless charger that form no part of the claimed design.

1 Claim, 9 Drawing Sheets(56)
